UNITED STATES PATENT OFFICE.

RAMON MARQUEZ, OF DETROIT, MICHIGAN.

FREEZING-ICES MACHINE.

Application filed February 7, 1925. Serial No. 7,676.

This invention relates to a freezing machine and has special reference to a machine for expeditiously and economically producing frozen edibles, for instance 5 flavored ices.

My invention aims to provide a machine of the above type in which flavored liquids, compounds or compositions may be frozen in a long stick formation, so that the frozen 10 sticks may be cut into desired lengths and served, or wrapped and preserved for future use. Special liquid containers are employed and provided with closures arranged so that 15 expansion of the frozen liquid, compound or composition, tends to tighten the closures, prevent leakage and condense or compact the frozen substances.

My invention further aims to provide a motor driven rotary brine holding cylinder 20 in which liquid containers may be arranged and retained circumferentially of the cylinder to provide a substantially central brine space. Rotation of the cylinder is adapted to cause the liquid brine to circulate about the liquid containers so that 25 the contents of the containers may be quickly frozen.

A novel construction and arrangement of parts enters into my machine which will 30 now be described by aid of the drawings, wherein

Figure 1 is a side elevation of the freezing machine;

Fig. 2 is a similar view, partly broken 35 away and partly in longitudinal section;

Fig. 3 is an end view of the machine, and Fig. 4 is a cross sectional view of the same.

The machine comprises a substantially 40 rectangular frame work having corner posts 1 and 2 provided with casters 3. The corner posts 1 and 2 are connected by longitudinal top rails 4 and gusset plates 5. In addition to the top rails 4 there are longitudinal bottom rails 5, transverse bottom rails 6 and intermediate transverse rails 7 which are additionally supported by A-frames or angularly disposed end braces 8.

Mounted on the intermediate transverse 50 rails 7 are bearings 9 for the pintles 10 of a cylinder 11 adapted to contain a freezing agent, as brine 12, and a large number of liquid containers 13. The liquid containers 13 are preferably tubular with inner closed 55 ends 14 adapted to be placed in abutting relation by placing the containers endwise

longitudinally of the cylinder and the outer ends of the containers are adapted to be closed by closures 15, preferably in the form of corks adapted to abut the end walls 16 of the cylinder. These containers are snugly 60 fitted within the cylinder so that any liquid, compound or composition within the containers cannot leak into the cylinder, and expansion of the liquid, compound or composition is adapted to tighten the closures 65 or corks in the outer ends of the containers. Freezing of the liquid within the containers also tends to more firmly compact or solidify the liquid because the closures or corks cannot tilt.

The liquid containers are arranged about the cylindrical wall of the cylinder and are adapted to be retained in a crescent-like cross sectional formation by resilient bowed members 16 which are sprung and fitted 70 within the cylinder as best shown in Fig. 4, to maintain a substantial central brine space, yet permit of the brine circulating about and between the liquid containers 75 when the cylinder is revolved.

The liquid containers are placed in the cylinder through a rectangular opening 17 having a cover 18 adapted to be clamped on the cylinder by a nut equipped bolt 19 provided with a cross bar 20 within the cylinder, said cross bar having its ends anchored against the inner wall of the cylinder.

The bottom rails 5 and 6 cooperate in supporting a brine box or receptacle 21 into which the brine 12 may be discharged when 80 the cylinder is to be emptied. The bottom rails also cooperate in supporting platforms 22 for an electric motor 23 and a gear housing 24. The electric motor 23 is of a conventional form adapted to be operated from 85 an electric light circuit or suitable source of electrical energy and the armature shaft 25 of said electric motor is suitably coupled, to a worm shaft 26 extending into the gear housing 24 with the worm shaft adapted for 90 driving a shaft 27 having a sprocket wheel 28 in the same vertical plane as the sprocket wheel 29 on one of the pintles 10 of the cylinder 11. An endless sprocket chain 30 is 95 trained about the sprocket wheels 28 and 29 so that the electric motor may drive the rotatable cylinder 11.

Suitable flavored liquids, compounds or compositions may be placed in the containers 13 and frozen to form sticks which can be 100

removed from the tubular containers, cut into desired lengths and served, or wrapped and preserved for future disposition.

The greater part of the machine is constructed of metal, but the resilient or bowed members 16 may be made of wood on account of being subjected to the brine and on account of being repeatedly sprung when placing the members in the cylinder for removing the same.

While in the drawing there is illustrated a preferred embodiment of my invention, it is to be understood that the structural elements are susceptible to such variations and modifications as fall within the scope of the appended claims.

What I claim is:—

1. A machine of the type described, comprising a driven rotatable cylinder adapted to contain a freezing agent, longitudinally disposed liquid containers in said cylinder and disposed end to end and against end walls of said cylinder, and means in said cylinder retaining said containers at the outer walls of said cylinder to form a substantially central brine space in said cylinder.

2. A machine of the type described, comprising a driven rotatable cylinder adapted to contain a freezing agent, longitudinally

disposed liquid containers in said cylinder, 30 bowed members at intervals in said cylinder retaining said containers at the outer walls of said cylinder to form a substantially central brine space in said cylinder and maintain a crescent-like cross sectional arrangement of said liquid containers in said cylinder.

3. A freezing machine comprising a driven rotatable brine holding cylinder, and liquid containers in said cylinder, said containers being tubular with detachable closures and arranged end to end so that end walls of said cylinder may retain the closures of said containers closed.

4. A freezing machine comprising a 45 driven rotatable cylinder adapted to contain a freezing agent, longitudinally disposed tubular containers in said cylinder, resilient members holding said containers circumferentially arranged within said cylinder and providing brine spacing, and means at one end of said cylinder for imparting rotation thereto.

5. A freezing machine as called for in claim 4, further characterized by a caster 55 equipped framework supporting said cylinder and the driving means thereof.

RAMON MARQUEZ.
